UNITED STATES PATENT OFFICE

PETER GRAHAM MACGREGOR, OF PEQUANOCK, NEW JERSEY, ASSIGNOR TO PYRENE MANUFACTURING COMPANY, OF NEWARK, NEW JERSEY, A CORPORATION OF DELAWARE

FIRE EXTINGUISHER

Application filed July 18, 1928. Serial No. 293,639.

My present invention relates to fire extinguishers of the pressure type and it has for its object to provide a device of this character wherein a highly compressible gas may be supplied in a fluid, or semi-liquid, state in a separate cartridge from which it may be released to expel the fire extinguishing liquid when required. To this end the invention also comprehends an improved arrangement 5 of parts for holding the gas cartridge within the extinguisher and maintaining the outlet of the latter normally closed together with the necessary operating devices for quickly releasing the contents of the cartridge and 10 permitting the escape of the extinguishing fluid under the effect of the pressure thus created.

A further object of this invention is to provide a fire extinguisher which is strong, 20 durable, light in weight and reliable in operation, thus rendering it particularly adapted for use in connection with airplanes and other similar crafts.

To these and other ends the invention consists in further improvements and arrangements of parts all of which will be more fully described in the following specification and distinctly pointed out in the appended 25 claims.

30 In the drawings:

Figure 1 is a view in elevation of an extinguisher embodying my invention showing the device in operating position; Figure 2 is a central longitudinal sectional view of the extinguisher showing the device in inverted or 35 loading position; Figure 3 is an enlarged sectional view showing in detail the cartridge-supporting and puncturing means; Figure 4 is a horizontal sectional view taken on the line 4-4' of Figure 3; Figure 5 is a horizontal sectional view taken on the line 5-5' of Figure 3; and Figure 6 is a view similar to Figure 3 and showing the cartridge and outlet seal in punctured condition after use.

40 The fire extinguisher illustrated as a commercial embodiment of my invention includes a shell 10 which serves as the liquid container and to one end of which is connected, as by brazing or soldering, a head 11 provided 45 with a filling opening through which the con-

tainer may be filled with fire extinguishing liquid and through which a sealed cartridge 12 carrying a compressed gas, such as carbon dioxide, may be inserted into the container and there held ready for use in operating 55 the extinguisher in the manner hereinafter more particularly described.

The closure for the filling opening of the receptacle 10 includes an internally screw-threaded bushing 13, connected at its upper end, by brazing or soldering, to the head 11. Also, the closure includes an externally screw-threaded plug 14, the head portion of which is provided with diametrically opposed arms 15 which serve as handles for screwing the 60 plug tightly into the bushing 13. The head portion of the plug 14 is formed with a screwthreaded socket, carrying therein pressure-applying head 17 from which extends a shaft 18 to the upper end of which is connected 65 a hand wheel 19, the shaft being surrounded by a split bushing nut 20 adapted to limit the outward movement of the head 17 within its socket when the hand wheel 19 is rotated in one direction.

70 For fracturing a normally closed seal, hereinafter more particularly described, which retains the fire extinguishing liquid within the receptacle 10 until the device is operated, a suitable seal fracturing member 75 is provided which is adapted to be actuated by the pressure-applying head 17 upon rotation of the hand wheel 19 and which is also independently operable. This seal-fracturing device is shown as a striking plunger 21 80 slidable through the head 17, the shaft 18 and the hand wheel 19, and provided at its outer end, which extends normally an appreciable distance beyond the hand wheel 19, with an impact head 22 to receive a blow 85 by which the striking plunger may be moved longitudinally so that its tapered end 23, which is normally positioned within an outlet chamber 24 formed in the lower end of the plug 14, may be forced through a suitable seal 90 95 26 which serves to normally retain the fire extinguishing liquid within the receptacle 10. For limiting the striking plunger 21 in its movement into operating position, its stem is provided with a disk-like 100

abutment 27 which is located adjacent one end of the pressure-applying head 17 and is adapted to engage the bottom of the socket in which that head operates. This disk-like abutment also prevents the striking plunger 21 from being withdrawn from its operating position by reason of the presence of the head 17 between which and the bottom of its socket the abutment is confined. In order to prevent the escape of liquid around the striking plunger 21 upon fracturing the seal 26, a suitable packing 28 is provided, such packing being located around the lower end of the stem of the striking plunger and confined within a stuffing-box 29 formed in the plug 14 adjacent the outlet chamber 24 and held under compression by a gland nut 30 through which the lower end of the striking plunger projects.

Depending from the screwthreaded bushing 13 is a cage-like support 30, the several arms of which are suitably spaced from each other to receive therebetween the cartridge 12 with its restricted neck portion resting upon the pointed end of a puncturing-pin 31 carried by the support at the juncture of the several arms thereof. This puncturing-pin is screwthreaded to the support and is longitudinally adjustable in order that a proper spacing of its pointed end from the seal 26 may be effected at the time of assembling to enable the cartridge 12 to be held, as shown in Figures 2 and 3, without permitting any undue longitudinal displacement of the cartridge during the handling of the fire extinguisher which may tend to cause accidental puncturing of the cartridge. When the proper adjustment of the pin 31 is once made, it may be secured in position by a lock-nut 33 carried at the lower end thereof and engageable with the cartridge support at the juncture of the several arms thereof.

In order that an effective liquid tight closure may be maintained between the receptacle 10 and the outlet chamber 24 may be insured when the seal 26 is introduced in preparing the extinguisher for use, the bushing 13 is provided at its lower end with a seal seat in the form of an annular flange 34 which is of appreciable length and is spaced a slight distance from the wall of the bushing, the flange being formed with a feather-edge so that when the plug 14 is forced down such edge is caused to slightly penetrate the surface of the seal. The efficiency of the seal thus produced is further augmented by providing the lower marginal face of the plug 14 with a depending annular flange 35, which, when the plug 14 is screwed down into engagement with the seal 26, engages the peripheral margin of that seal and forces the same down into the space between the flange 34 and the inner wall of the bushing 13, the inner diameter and inclination of

the inner wall of the flange 35 being such with respect to the outer diameter and inclination of the flange 34 that the downwardly turned peripheral margin of the seal 26 is effectively clamped in place between the flanges 34 and 35 and in intimate engagement therewith.

At the outlet end of the receptacle 10 a discharge nozzle 37 is provided which is suitably connected to the bottom wall of the receptacle to form a liquid tight union therewith. This nozzle is connected by a discharge pipe 38 to a receiving chamber 39 formed in an offset or extension 40 carried by the bushing 13, the chamber 39 being in communication with the discharge chamber 24 by way of a plurality of ports 41 leading radially from the discharge chamber into the annular space 42 formed intermediate the plug 41 and bushing and communicating with the receiving chamber.

To operate the extinguisher, it is held with its discharge nozzle 37 pointing generally upwardly, as shown in Figure 1, whereupon the striking plunger 21 is subjected to a blow, thereby causing it to move longitudinally within the head 17, shaft 18 and hand wheel 19. Upon such movement of the striking plunger, its beveled end is forced through the seal 26 thereby causing the cartridge 12 to move longitudinally within its support 30 with the result that the puncturing pin 31 is forced through the end of the cartridge. When the cartridge is punctured, its contents are released, thereby setting up a pressure within the receptacle 10 which is utilized to force the liquid therefrom through the punctured seal into the outlet chamber 35 from which it passes to the receiving chamber 39 and out through the discharge tube 38 and nozzle 37 to be directed upon the fire. In the event conditions are such, when it is desired to operate the extinguisher, as to make impossible the delivering of a blow to the striking plunger 21, operation of the extinguisher may be effected by operating the hand-wheel 19 whereupon the pressure-applying head 17 engages the abutment and forces the plunger through the seal 26 and causes the cartridge 12 to be punctured by the puncturing-pin 31, whereupon the contents of the receptacle 10 are discharged as described.

While only one form of the invention is herein shown and described, it will be understood that various changes may be made without departing from the spirit of the invention and the scope of the following claims.

What I claim is:

1. A fire extinguisher comprising a liquid receptacle having an outlet, a seal normally closing said outlet, a sealed cartridge containing a compressed gas to be released in said receptacle, a seal-fracturing device for opening said outlet, and cartridge-puncturing means cooperating with said seal-fracturing

ing device to release the contents of said cartridge.

10. A fire extinguisher comprising a liquid receptacle having a filling opening, a closure for said opening having a seal seat and including a bushing and a plug therein, the latter being provided with an outlet chamber, a discharge tube communicating with said chamber and leading out of said receptacle, a seal overlying said chamber and confined between said seat and plug, a seal-fracturing device longitudinally movable in said plug, cartridge-puncturing means, and a sealed cartridge containing a compressed gas to be released in said receptacle, said cartridge being located intermediate said seal-fracturing device and said cartridge-puncturing means, whereby said cartridge-puncturing means is rendered effective upon operation of said seal-fracturing device to release the contents of said cartridge.

In testimony whereof I have affixed my signature to this specification.

PETER GRAHAM MacGREGOR.
